UNITED STATES PATENT OFFICE.

HYMAN GUTTMAN, OF NEW YORK, N. Y.

DESIGN FOR A KNITTED FABRIC.

Application filed November 28, 1922. Serial No. 4,432. Term of patent 3½ years.

To all whom it may concern:

Be it known that I, HYMAN GUTTMAN, a citizen of the United States, residing at New York, in the county of New York and State of New York, have invented a new, original, and ornamental Design for Knitted Fabrics, of which the following is a specification, reference being had to the accompanying drawing, forming part thereof.

The figure is a plan view of a knitted fabric, showing my new design.

The design is produced by forming the threads of the fabric into loops at predetermined points which loops are superposed upon the main body of the fabric and interwoven therewith at spaced intervals.

I claim:

The ornamental design for a knitted fabric substantially as shown and described.

HYMAN GUTTMAN.
